UNITED STATES PATENT OFFICE.

GEORGE BRODIE, OF JEFFERSON COUNTY, ARKANSAS.

IMPROVEMENT IN COTTON-BALE TIES.

Specification forming part of Letters Patent No. 129,925, dated July 30, 1872; antedated July 26, 1872.

To all whom it may concern:

Be it known that I, GEORGE BRODIE, of the county of Jefferson and State of Arkansas, have invented certain new and useful Improvements in Cotton-Bale Ties, of which the following is a full, clear, and exact description, reference being had to the accompanying drawing and to the letters of reference marked thereon, making part of this specification, in which—

Figure 1 is a top-plan view. Fig. 2 is a vertical sectional view on the line $x x$, Fig. 1. Fig. 3 is a bottom-plan view.

My present improvement in bale-ties consists simply in a new article of manufacture, and as such alone lays claim to novelty, for it is nothing but an improvement on one of the devices embraced in and distinctly covered by reissue No. 3,405 granted to me April 27, 1869, and which was a reissue of my original patent No. 23,291, dated March 22, 1859.

The device referred to forms the distinctive subject-matter of the first claim of said reissue, and is distinctly shown in Figs. 1 and 3 of its accompanying drawing.

The difficulty with the bale-tie fastening referred to, and to remedy which is the object of my present invention, is, that the pins which form the bearings for the heads of the oblate hooks formed on the ends of the band or hoop are independent or detachable, and consequently, before the fastening is effected, they are always liable to drop out of the hook, and which is not only a subject of much annoyance, but not unfrequently the pins are lost, which renders it impossible to secure the band in the manner stated.

In my present improvement this objection is entirely remedied, and the means by which the same is effected constitute the very essence of my invention.

Instead of forming the bearing-pins for the oblate hook independent or detachable, I construct them with the tie-plate or buckle, and semi-cylindrical in form, so that they are a permanent component part of the same. The bars in my present tie, which are the equivalents of the detachable pins of the reissue, are so arranged that they are not in the same plane with the end bars of the tie, but bear the exact relative position to the end bars

that the detachable pins of the tie embraced in the first claim of my reissue do when the fastening is effected as therein embraced and covered.

The construction and operation of my invention are as follows: A is the bale-tie plate or buckle, and is manufactured by any of the well-known processes, and out of any suitable metal. From the upper and lower faces of this plate project semi-cylindrical bearing-bars B B and C C. The tie is so formed and the bars B B and C C are relatively so arranged thereon as to leave a center opening or slot, A', between the bars C C, through which the ends of the band are first introduced in effecting a fastening, and two end openings or slots, a a, one of which is between each pair of bars B C, and through which openings the ends of the bands are passed after they have been looped around the bars C C. D is the ordinary metallic hoop or band, secured around the bars C C, its ends being part under said bars and over the bars B B, as shown in Fig. 2, the security of the fastening being attained by the action of the expansive force of the bale.

The value of the tie constructed on this principle is its immense strength. After thorough tests, practical experience has demonstrated the fact that with the same weight of metal it will withstand more pressure than any other form of tie now in use.

What I claim as new, and desire to secure by Letters Patent of the United States, is—

As a new article of manufacture, the buckle or tie A, provided with a center opening, A', transverse slots a a near its ends and semi-cylindrical bars B B and C C on its upper and lower faces, all constructed and relatively arranged for operation in the manner specified, in connection with the band or hoop ends D, attached and secured as shown and described, for the purpose set forth.

In testimony whereof I have signed my name to this specification in the presence of two subscribing witnesses.

GEORGE BRODIE.
